US0D1072815S

(12) **United States Design Patent** (10) **Patent No.:** **US D1,072,815 S**
(45) **Date of Patent:** **** Apr. 29, 2025**

(54) **KEYBOARD**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, San Francisco, CA (US); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/932,173**

(22) Filed: **Mar. 12, 2024**

Related U.S. Application Data

(63) Continuation of application No. 29/863,013, filed on Dec. 14, 2022, now Pat. No. Des. 1,027,950, which is

a continuation of application No. 29/756,646, filed on Oct. 29, 2020, now Pat. No. Des. 976,906.

(51) **LOC (15) Cl.** **14-02**

CLAIM

The ornamental design for a keyboard as shown and described.

DESCRIPTION

FIG. 1 is a perspective view of a keyboard showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the portion encircled in FIG. 1.

The broken lines depict portions of the keyboard which form no part of the claimed design.

The dot-dot-dash broken lines depict an area of enlargement.

1 Claim, 6 Drawing Sheets
